SURFACE TESTER

Fred H. Benjamin, Pittsburgh, Pa.

Application August 3, 1935, Serial No. 34,558

2 Claims. (Cl. 73—51)

My invention relates to novel apparatus for testing the surface wear of a fibrous material, and more specifically relates to a novel jute liner surface tester or scuff tester.

5 Objects of my invention are to provide novel apparatus for testing the surface of fibrous material which is inexpensive, simple and accurate; and a novel jute liner surface tester.

There are other objects of my invention which 10 together with the foregoing will appear in the detailed description which is to follow in connection with the drawing, in which:

Figure 1 is a sectional side view on line 1—1 of Figure 2.

15 Figure 2 is a plan view.

Figure 3 is a sectional view on line 3—3 of Figure 1.

20 Referring to Figure 1, a rectangular block 5 of convenient dimensions around which the paper P desired to be tested is wrapped in a manner to permit the ends of the paper to overlap under the lower face of block 5 so that when the said block is forced into the frame F, the paper is held thereon securely.

25 As shown in Figures 1 and 2, the block 5 fits snugly between the end blocks 6 and 7 of the frame, which are mounted on the base 8.

30 A slidable upper block 9 of considerably smaller dimensions than the lower block 5 is used to carry a similar surface of paper P' on its periphery and is held tightly by a plug type member 10 which fits snugly in the cut-out formed in the block 9.

35 In the center of the plug-block 10 a longitudinal slot as at 11 is cut-out to permit the semi-circular head 12 of support 13 to enter and freely rotate therein. A platform 14 carrying a weight 15 is mounted on the support 13. Extending from the platform 14, a tie-rod 16 of any 40 desired shape and length serves as the crank rod for the crank pin 17 which is mounted on the rotating plate 18. The plate 18 is driven through the reduction gear box 19 by the motor M, which is mounted together with the reduction mechanism as a unit on the base 21. As will be seen in Figure 1, the crank pin will cause the platform 14 to have reciprocating motion carrying with it the support 13 and block 9 on which the

paper is wrapped (as indicated in dotted lines) thus producing the desired friction of the paper P' upon P. The block 9 is guided between two guides 22 and 23.

5 While I have shown a specific mode of carrying out my invention, it must be understood that this may be departed from without departing from the scope or spirit of my invention, and I do not intend to be limited except by the following claims.

10 I claim:

1. An apparatus for testing paper manufacture which comprises a frame, a removable block adapted to be held securely in place by said frame and adapted to have a layer 15 of the material to be tested overlapping the under surface of said block to be secured thereto, said frame comprising a pair of members engaging said block and securing said paper thereto, a second block for carrying a second layer 20 of material to be tested, a removable plug seated in said second block for securing said second layer of material to said second block, said plug having a slot therein, a head seated downwardly in said slot for free rotation therein, a 25 platform carrying a weight for maintaining said head seated in said slot, a bellcrank, a tie-rod connecting said platform to said bellcrank and a motor for driving said bellcrank.

2. An apparatus for testing paper manufacture which comprises a frame, a removable block adapted to be held securely in place by said frame and adapted to have a layer of the material to be tested overlapping the under surface of said block to be secured thereto, said 30 frame comprising a pair of members engaging said block and securing said paper thereto, a second block for carrying a second layer of material to be tested, a removable plug seated in said second block for securing said second layer 35 of material to said second block, said plug having a slot therein, a head seated downwardly in said slot for free rotation therein, a platform carrying a weight for maintaining said head seated in said slot, and means including a motor 40 for reciprocating said platform.

FRED H. BENJAMIN.
